UNITED STATES PATENT OFFICE

2,110,494

VENTILATED BUFFING WHEEL

Harry Zimmerman, Toronto, Ontario, Canada

Application February 16, 1937, Serial No. 126,014

5 Claims. (Cl. 51—193)

My invention relates to improvements in ventilated buffing wheels of the type disclosed in my United States Patent application, Serial No. 68,403, filed March 12th, 1936, wherein fan members are positioned at the sides of a buffing wheel to rotate therewith and inject air into the central portion of the wheel from where it passes outwardly between either the buffing sections or plies of the wheel to dissipate frictionally generated buffing heat.

The object of my present invention is to provide an improved means for securing the fan members and buffing wheel sections in assembly whereby the air draft receiving orifices in the central portions of the buffing wheel sections or plies are retained in their proper alignment.

To attain the object of my invention, I provide the fan members with a plurality of pins which are directed inwardly about the arbour hole of the buffing wheel and contained within the pear-shaped air draft receiving orifices as disclosed in my United States Patent application, Serial No. 68,403.

Another object of my invention is to provide a pair of clamping flanges in lieu of fan members in cases where it is desired to use a non-ventilated buffing wheel, and to provide such flange members with pins which pass through orifices in the buffing wheel in substantially the same manner as the pins on the fan members which project through the air draft receiving orifices in a ventilated buffing wheel.

A further object of my invention is to so design the fan members that each is furnished with a plurality of pins and a plurality of pin receiving orifices, the orifices in one fan member receiving the outer ends of the pins of the other fan member, and another object of my invention is to provide a fan member construction wherein the pins are rigidly secured against accidental displacement and wherein longer or shorter pins can be readily substituted in a fan member if so desired.

With these and other objects in view, my invention consists in the provision of a ventilated buffing wheel constructed and arranged all as hereinafter more particularly described and illustrated in the accompanying drawings in which,

Figure 1 is a perspective view of a pair of my fan members apart from a buffing wheel.

Figure 2 is a perspective view of a buffing wheel adapted to receive a pair of fan members as illustrated in Figure 1.

Figure 3 is a cross-sectional view through a

buffing wheel assembly, the outer periphery of the wheel being broken away.

Figure 4 is a similar view to Figure 3 showing an alternative construction wherein the pins do not extend from fan member to fan member, and also showing the use of separator discs positioned between the buffing wheel sections.

Figure 5 is a cross-sectional view through a wheel, such section being taken through the line 5—5, Figure 3.

Figure 6 is a plan view of one of the separator discs as incorporated in my assembly shown in Figure 4.

Figure 7 is a plan view of an alternative form of separator disc construction.

Figure 8 is a reduced cross-sectional view through a buffing wheel section showing such section made up of a plurality of sector shaped pieces arranged around the arbour hole and pierced by my pins, and

Figure 9 is a reduced side elevational view of a pair of buffing wheel engaging flanges provided with my pins but not provided with fan blades and adapted to be used in connection with a non-ventilated buffing wheel as shown in Figure 8.

Like characters of reference indicate corresponding parts in the different views of the drawings.

The buffing wheel as described in my pending application, Serial No. 68,403, consists of a plurality of sections or plies of buffing fabric which are assembled to form the buffing wheel, and which are pierced with a plurality of orifices arranged around the arbour hole of the wheel for the admittance of an air draft.

In my present application, Figures 2 and 3, I show the buffing wheel as made up of a plurality of sections 1 which are suitably thickened at their central portions 2 and pierced by a plurality of substantially pear-shaped orifices 3 arranged around the central arbour holes 4. The sections are carried upon a buffing lathe spindle 25, as is standard practice. By thickening the central portions 2 of the sections, the outer peripheral portions of the sections are spaced apart a slight degree to permit air injected into the orifices 3 to pass outwardly from the wheel between the sections 1. In the case of a loose buff, wherein the plies of material that form the wheel are not sewn together at their outer portions, the injected air draft passes outwardly between the plies.

The injected air draft is supplied by a pair of fan members which are also carried upon the buffing lathe spindle and positioned at the sides

of the buffing wheel. The fan members each consist of a hub 5 having a central spindle receiving orifice 6, and a plurality of fan blades 7 radiating from the hub and having their outer ends secured to the inner face of a ring 8 which surrounds the hub 5.

In order to obtain the desired results from my buffing wheel assembly, the air draft orifices 3 in the sections or plies must be retained in alignment so that the injected air may freely pass through the wheel and out between the sections or plies. If the orifices 3 were not retained in proper alignment with one another, the solid portion of one section might conceivably register with an orifice in an adjacent section, whereby the air draft injected into such orifice would be blocked by the section which was out of alignment.

To overcome any possibility of the orifices in the sections moving out of alignment and also to facilitate the assembly of the sections into a wheel, I provide each of the fan members with a plurality of pins 9 which extend from the inner faces of the hubs 5 through the orifices 3 in the buffing wheel sections. The pins 9 are arranged around the arbour holes 6, and as illustrated in Figure 1, each fan member carries three equidistantly spaced apart pins and is also pierced by three similarly arranged orifices 10 which receive the outer ends of the pins of the opposite fan member, as illustrated in Figure 3. The pins are positioned to be contained within the inner portions 11 of the pear-shaped orifices 3, as illustrated in Figure 5, and are of such a diameter that they snugly fit in such portions 11 of the orifices 3 and do not obstruct the passage of air through the major portions of the orifices. When the sections and fan members are assembled, the pins retain the sections against independent movement.

The fan members can be constructed of metal, or of a material such as rubber, and in practice I have formed them of moulded aluminium. As it is desirable to have the pins 9 securely mounted upon the hubs 5, and as such hubs 5 receive the tightening pressure of the nut 12 on the lathe spindle 25, I provide steel plates 13 on the outer faces of the hubs. The plates 13 are pierced by the orifices 10 and also carry the inner ends of the pins 9. Upon reference to Figure 3 it will be seen that the plates 13 are each formed with countersunk orifices 14 in which the ends 15 of the pins 9 are riveted. The orifices 14 and the ends 15 of the pins are so arranged in proportion to the diameter of the pins that when the ends of the pins are riveted in place, the pins are tightly secured to the plates. The three pins on a plate 13 are inserted through three orifices 16 in a hub 5 and the plate 13 secured to the hub by two or more screws 17 which pass through the plate into the hub.

The plates 13, being made of steel, do not cut under the drawing up pressure of the nut 12 as would be the case if the nut was bearing against the aluminium hub 5, and also if it is desired to use longer or shorter pins 9, they can be readily removed from the hub as a group by taking out the screws 17 and pulling the plate 13 away from the hub 5. A new plate 13 carrying replacement pins is then repositioned upon the hub. As the pin end receiving orifices 10 extend right through the hubs 5 and plates 13, it will be understood that in cases where a relatively thin buffing wheel is used that the ends of the pins

will extend right through the orifices 10 and project outwardly from the plate 13.

In Figure 4, I show an alternative construction wherein short pins 18 are furnished in lieu of the longer pins 9. The pins 18 are provided of such a length that they will extend more than half way into a wheel of average thickness. Thus the pins on one fan member will project into the adjacent half of the wheel and the pins on the other fan member project into the other half of the wheel. In this construction the hubs 5 and plates 13 carry the pins 18 but are not provided with the pin end receiving orifices 10. The assembly in Figure 4 shows the use of several buffing sections 19 which are not thickened at their centers as is the case with the sections 1

To space apart the sections 19 I furnish a number of separator discs 20 which are positioned between the sections to space them apart and thus provide the air passages between the sections. The discs shown in Figure 4 are each of the same form as the disc shown in Figure 6 wherein the disc is formed with a central spindle receiving arbour hole 21 and six peripherally arranged orifices 22 through which either the pins 9 or the pins 18 extend. In Figure 7, I show an alternative form of disc 23 having six substantially V-shaped pin receiving slots 24 in its periphery. These slots have substantially the same contour as the inner portions 11 of the orifices 3 in the sections, and in this construction it is possible to have the discs 23 of greater diameter than is the case with the discs 20, as the open ends of the slots 24 do not obstruct the free passage of air through the wheel. The discs 20 and 23 can be made of any desirable material, either stiff or flaccid.

In Figure 8, I show a buffing wheel section 26 made up of a plurality of sector shaped portions 40 27 which are arranged around a central arbour hole 28. In order to retain such an assembly in position, I can use a pair of flanges 29 and 30 such as illustrated in Figure 9, wherein the flange 29 is provided with a plurality of pins 31 which project 45 through orifices 32 in the sectors. The pins 31 enter orifices 33 provided in the flange 30. Alternatively the flanges 29 and 30 can be each provided with a set of pins in the same manner as already described in regard to the fan member. 50 The pins 31 passing through the orifices 32 retain the sectors 27 against any outward centrifugal movement when the buff is in operation. The sectors 27 are also sewn to circular discs of fabric which are included in the buff section assembly. 55 The flanges 29 and 30 are, of course, also pierced with arbour holes 34 for the reception of the buffing lathe spindle. The nut 12 clamps against one of the flanges as is standard practice.

From the foregoing description it will be apparent that I have provided a very simple and practical construction for retaining my draft creating fan members and buffing wheel sections in their aligned relationship, and although I have shown a specific construction of my assembly, it is to be understood that I can make such changes and alterations as I may from time to time deem necessary without departing from the spirit of my invention as set forth in the appended claims.

What I claim as my invention is:

1. A pair of fan members for use in combination with a ventilated buffing wheel each comprising a central hub, a plurality of fan blades radiating therefrom, a plurality of pins arranged in parallel equi-distant relationship around an 75

arbour hole in the hub, each of the hubs also having a plurality of orifices arranged around the arbour hole and adapted to receive the outer ends of the pins of the other fan member.

5. 2. A ventilated buffing wheel pierced with an arbour hole and also pierced with a plurality of air inlet orifices positioned around and spaced away from the arbour hole, a fan member positioned to be rotatable in unison with the buffing wheel, a fan member hub partly overlapping the air inlet orifices, and a plurality of pins projecting from the fan member hub and contained within the portions of the air inlet orifices adjacent to the arbour hole of the buffing wheel.

15. 3. A ventilated buffing wheel pierced with an arbour hole and also pierced with a plurality of orifices arranged around the arbour hole and spaced away therefrom, a pair of fan members positioned at the sides of the wheel to be rotatable in unison therewith, fan member hubs partly overlapping the air inlet orifices, a plurality of pins projecting from each fan member hub through the portions of the orifices adjacent to the arbour hole in the buffing wheel and having their outer ends contained within orifices in the

fan member hub oppositely positioned to the fan member hub from which they project.

4. A ventilated buffing wheel pierced with an arbour hole and also pierced with a plurality of substantially triangular shaped air inlet orifices 5 spaced around the arbour hole, a fan member positioned to be rotatable in unison with the buffing wheel, a fan member hub partly overlapping the air inlet orifices, and a plurality of pins projecting from the fan member hub into 10 the buffing wheel and contained within the apex portions of the air inlet orifices adjacent to the arbour hole of the buffing wheel.

5. A ventilated buffing wheel pierced with an arbour hole and also pierced with a plurality of 15 air inlet orifices positioned around and spaced away from the arbour hole, a circular wheel clamping member positioned to rotate in unison with the buffing wheel and being of such a diameter as to partly overlap the air inlet orifices, 20 and a plurality of pins projecting from the orifice overlapping portion of the wheel clamping member and contained within the portions of the air inlet orifices adjacent to the arbour hole of 25 the buffing wheel.

HARRY ZIMMERMAN.
